UNITED STATES PATENT OFFICE

2,575,826

DRILLING TOOL

John W. Mecom, Houston, Tex.

Application March 10, 1947, Serial No. 733,501

3 Claims. (Cl. 255—27)

1
This invention relates to a drilling tool of the percussion type.

An object of the invention is to provide a tool of the character described comprising a drill and a drill collar with an anvil secured to the upper end of the collar in combination with a rotatable hammer connected to the lower end of a coupling which is connected to, and adapted to be rotated by, a drill stem whereby the hammer will be rotated to impart successive blows to the anvil and hence to the drill.

It is another object of the present invention to provide, in an assembly of the character described, a housing connected to the drill collar and sealed with said coupling to exclude gritty fluids from the operating parts.

The invention also includes clutch means whereby the drill stem may be clutched with the drill for simultaneous rotation in case it is desired to rotate the drill for reaming purposes.

The invention also includes a novel type of drill which will be gradually rotated about the bottom of the bore as successive hammer strokes are imparted whereby the formation at the bottom of the bore will be gradually disintegrated as drilling progresses.

The invention also embodies novel means for supplying drilling fluid to the operative face of the drill.

With the above and other objects in view the invention has particular relation to certain novel features of construction, operation and arrangement of parts, an example of which is given in this specification and illustrated in the accompanying drawings, wherein:

Figure 1 is a side elevation, partly in section, of the upper end of the tool.

Figure 2 is a side elevation, partly in section, of an intermediate section of the tool in position for percussion drilling.

Figure 3 is a side elevation, partly in section, of the lower end of the tool.

Figure 4 is a side elevation, partly in section, of the upper end of the tool showing the clutch engaged.

Figure 5 is a side view, partly in section, of the lower end of the tool showing the relative position of the parts when the clutch is engaged, and

Figure 6 is a side view, partly in section, of the complete tool with the parts in position for percussion drilling and showing the opposite side from that shown in Figure 2.

Referring now more particularly to the drawings wherein like numerals of reference designate

2
the same parts in each of the figures, the numeral 1 designates the drill to the upper end of which the drill collar 2 is connected.

Attached to the upper end of the drill collar 5 there is the tubular anvil 3.

The upper end face of this anvil is formed with correspondingly inclined faces, as 4, 4 which terminate in oppositely arranged abrupt vertically disposed shoulders, as 5, 5.

Above the anvil 3, and in axial alignment therewith, there is the tubular hammer 6 whose lower end is formed with correspondingly inclined faces 7, 7 which are pitched to ride on the faces 4, 4 as the hammer rotates and these inclined faces 7, 7 terminate in vertically disposed shoulders 8, 8.

As the hammer rotates the faces 7 will ride up along the faces 4 until the shoulders 8 pass the corresponding shoulders 5 and the hammer will then drop by gravity imparting a stroke to the anvil. As illustrated there will be two hammer strokes imparted to the anvil with each rotation of the hammer.

There is a wash pipe 9 whose upper end is screwed into the lower end of the hammer and whose lower end extends down into and through the anvil.

Suitable sealing rings 10 surround the wash pipe and are clamped between an inside annular shoulder 11 in the anvil and a gland 12 which is screwed into the anvil and abuts said seal rings.

The upper end of the hammer is formed with suitable jaw clutch teeth 13.

There is an elongated tubular coupling 14 whose lower end is screwed into the upper end of the hammer 6 and to whose upper end the operating drill stem 15 is connected.

There is a tubular housing 16 which is fitted closely around the anvil and hammer and whose lower end is threaded onto the upper end of the drill collar 2.

The upper end of this housing is provided with the coarse internal threads 17. A tubular clutch member 18 is fitted closely around the coupling 45 14 and its lower end is threaded into the upper end of the housing 16. Its upper end is enlarged internally forming an inside, annular, upwardly facing shoulder to support the seal rings 20 which surround the upper end of the coupling 14 and this seal is clamped in place by means of a gland 21 screwed into the upper end of the clutch member 18.

Above the gland 21 the coupling 14 is enlarged in external diameter so as to be approximately flush with the assembly beneath.

The lower end of the clutch member 18 is formed with the jaw clutch teeth 22 adapted to be brought into and out of clutching relation with the jaw clutch teeth 13. In carrying on ordinary drilling operations the drill 1 will rest on the bottom of the bore and the hammer 6 will be in cooperating relation with the anvil 3, as shown in Figure 6, with the clutch disengaged so that as the drill stem 15 is rotated rotation will not be imparted to the housing 16 or to the drill but the hammer will rotate relative to the anvil and impart successive strokes thereto as hereinabove explained.

The drill may be provided with a pilot 23, preferably formed with teeth which converge downwardly. This pilot holds the drill centered relative to the bore and thus conduces to a straight bore hole.

On the underside of the drill spaced outwardly from the pilot are the substantially radial cutting teeth 24 which are pitched slightly forwardly so that with each downward stroke of the hammer the drill will not only be forced downwardly but will be caused, by the pitch of the teeth, to partially rotate to the end that the successive strokes will impart successive partial rotations to the drill. This turning movement of the drill is accelerated by the sloping faces 7 striking the sloping faces 4.

As is shown in Figure 3 the drill is hollow and leading outwardly from the interior of the drill are the outer and inner channels 25 and 26, suitably spaced apart around the drill and through which the drilling fluid forced down through the drill stem and tool may be supplied to the formation underneath the drill to carry away the cuttings. The inner surfaces of these passageways 25 and 26 may be formed with hardened material to reduce the abrasive effect of the drilling fluid and the cutters of the pilot and drill should also be hard surfaced as is now common practice.

In the course of carrying on drilling operations it may be desirable to ream the bore whereupon the drill stem may be moved upwardly until the teeth 13 engage the teeth 22 and thereafter upon rotation of the drill stem the drill will be rotated with it and may be moved up and down in the bore hole until the reaming operations are completed.

The wash pipe 9 has been provided so that in either position of the tool, whether drilling, as shown in Figure 2, or reaming, as shown in Figure 5, the drilling fluid will be excluded from the operative parts of the tool, particularly from the anvil and hammer.

The drawings and description are illustrative merely while the broad principle of the invention will be defined by the appended claims.

What I claim is:

1. A drilling apparatus comprising, a rotatable stem, a drill associated with the stem and rotatable independently thereof, a hammer carried by the stem and rotatable therewith, clutch means on the upper end of the hammer, an anvil on the drill, contacting inclined faces on the hammer and anvil respectively and forming means for alternately lifting the hammer and permitting the same to drop to impart successive strokes to the anvil and also to impart successive partial rotations to the anvil and drill, a housing connected to the drill and fitted closely about the anvil and hammer and slidably longitudinally relative to the hammer, a clutch member around the stem secured to the upper end of the housing

and having clutch means thereon adapted to interengage with and disengage from the clutch means on the hammer upon relative longitudinal movement between the housing and hammer.

2. A drilling apparatus comprising, a rotatable drill stem, a hammer secured to the lower end of the stem whose upper end is formed with clutch teeth, a drill having a drill collar thereon, an anvil secured to the upper end of the drill collar in axial alignment with the hammer, contacting inclined faces on the hammer and anvil respectively and forming means for alternately lifting the hammer and permitting the same to drop, upon rotation of the hammer, to impart successive strokes to the anvil, a housing around the anvil and hammer and whose lower end is secured to the drill collar, said hammer and housing being adapted for relative longitudinal movement, a clutch member spaced above the hammer and surrounding the drill stem and secured to the upper end of the housing, the lower end of said clutch member being formed with clutch teeth adapted to interengage with the clutch teeth on the hammer, upon upward movement of the hammer relative to the housing to clutch the stem with the housing whereby the apparatus will rotate as a unit, said hammer being rotatable independently of the housing upon downward movement of the hammer relative to the housing to disengage the clutch teeth on the clutch member from the clutch teeth on the hammer.

3. A drilling apparatus comprising, a rotatable drill stem, a tubular hammer secured to the lower end of the stem and whose upper end is formed with clutch teeth, a drill having a tubular drill collar thereon, a tubular anvil secured to the upper end of the drill collar in axial alignment with the hammer, contacting inclined faces on the hammer and anvil and forming means for alternately lifting the hammer and permitting the same to drop, upon rotation of the hammer, to impart successive strokes to the anvil, a tubular housing around the anvil and hammer whose lower end is secured to the drill collar, a clutch member spaced above the hammer and surrounding, and in sealing relation with, the drill stem and secured to the upper end of the housing, the lower end of said clutch member being formed with clutch teeth adapted to interengage with the clutch teeth on the hammer upon elevation of the hammer, to clutch the stem with the housing whereby the apparatus will rotate as a unit, a wash pipe whose upper end is secured to the lower end of the hammer and whose lower end extends down into and through the anvil when the hammer is in either of its positions and a seal between the wash pipe and the anvil.

JOHN W. MECOM.
